MARBLE RUNWAY NOVELTY DEVICE

James D. Hughes, 4714 Spellman,
Houston, Tex. 77035

Filed Nov. 23, 1970, Ser. No. 26,122

Term of patent 14 years

Int. Cl. D21—01

U.S. Cl. D34—15

FIG. 1

FIG. 2

FIG. 3

FIG. 4

FIG. 1 is a perspective view of a marble runway novelty device showing my new design;

FIG. 2 is a side elevational view thereof;

FIG. 3 is a top plan view thereof; and

FIG. 4 is an end view taken from the left side of FIG. 1.

I claim:

The ornamental design for a marble runway novelty device, substantially as shown.
